ATTORNEY

UNITED STATES PATENT OFFICE

CHARLES H. GAGEN, OF MONTCLAIR, NEW JERSEY, ASSIGNOR TO AMERICAN AIR FILTER COMPANY, INC., OF LOUISVILLE, KENTUCKY, A CORPORATION OF DELAWARE

SELF-SEALING FILTER

Original application filed June 20, 1928, Serial No. 286,771. Divided and this application filed October 18, 1930. Serial No. 489,576.

This invention relates to self-sealing filter construction and is a division of my co-pending application, Serial #286,771, filed June 20, 1928 now Patent #1,821,211, issued September 1, 1931. This co-pending application discloses a filter construction in which filter cells or units are mounted or adapted to be mounted on a suitable frame. The cells therein shown are of a special or double passage type being formed with passages that open at the front and rear of the cell unit for the passage of the air stream and at the top and bottom for the passage of a filter cleaning medium. Such application is directed to means for sealing the top and bottom cleaning openings when the filter is in its operative or air filtering position. It is also directed to means for preventing the passage or leakage of air between the cell unit and the frame upon which it is mounted. It is to this latter feature that the present invention is specifically directed. The principal object of the invention is to provide a cell which may be positioned on a frame simply by hooking the cell thereto, and which when positioned will by virtue of its weight tend to maintain such close engagement with the frame as to prevent the passage or leakage of air between the unit and the frame.

An embodiment of the invention is illustrated in the accompanying drawing, wherein:

Figure 1 is a fragmentary front elevation of a suitable supporting frame, showing in dotted lines the area of the frame covered by a cell unit;

Figure 2 is a sectional view taken along line 2—2 of Figure 1, showing a filter cell in top plan view; and

Figure 3 is a sectional view taken along line 3—3 of Figure 1, with a filter cell in operative position.

In carrying out the invention a frame for the support of one or more cells is provided which is composed of vertical and horizontal

members 70 and 71 arranged to form rectangular openings 72 therein. A filter cell or unit indicated generally at 73 is adapted to be placed in front of each such recess 72 and the air drawn through the same in the direction of the arrow 74. The cell 73 overlaps the respective frame members all around the edges of the opening 72 to a desired distance as indicated by the dotted lines 75 in Figure 1. Each cell has adjacent to the upper ends of its two vertical side wall members two hooks or suspending devices 76 suitably secured thereto. The hooks 76 are adapted to be hung into and thru appropriate recesses 77 cut in the flanges of the vertical T frame members 70. The inner or under edge 78 of the projecting portion 79 of the hook device 76 is formed with an inclined surface so that when the cell is suspended in its proper position the plane of engagement between the hook and frame inclines downwardly away from the unit. As a result of this mode of engagement the weight of the cell 73 will tend to draw the cell tightly against the respective overlapped surfaces of the vertical and horizontal T frame members 70 and 71 and thereby seal the edges of the opening 72. With the edges sealed it is obvious that the air will be prevented from passing around the side, top and bottom walls of the cell and between the frame and cell unit as a whole and will thereby be compelled to pass into the filtering passages before escaping to the clean air side of the filter cells.

Having described my invention, I claim:

In a filter the combination of a frame presenting a unit receiving opening, the frame being formed with recesses at the sides of each opening, a unit adapted to be positioned with its edges on one side overlapped by vertical frame surfaces adjacent said opening, and inter-engaging means between said unit and the frame whereby when the unit is operatively positioned its weight constantly tends to maintain in close engagement the

overlapping surfaces between said unit and frame so as to prevent the passage of air therebetween, said means comprising hooks secured to the side walls of the unit and adapted to extend into said recesses so as to engage the frame and thereby support the unit thereon, the planes of engagement between the hooks and frame inclining downwardly away from the unit.

10 In testimony whereof, I hereunto affix my signature this first day of October, 1930.

CHARLES H. GAGEN.
